US00D825114S

(12) **United States Design Patent** (10) **Patent No.:** **US D825,114 S**
Robbins et al. (45) **Date of Patent:** **** Aug. 7, 2018**

(54) **FEED STAND**

- (71) Applicants: **Jerry D Robbins**, Grand Junction, CO (US); **Joyce A Schaefer**, Grand Junction, CO (US)
- (72) Inventors: **Jerry D Robbins**, Grand Junction, CO (US); **Joyce A Schaefer**, Grand Junction, CO (US)

(**) Term: **15 Years**

(21) Appl. No.: **29/624,114**

(22) Filed: **Oct. 30, 2017**

(51) LOC (11) Cl. **30-03**

(52) U.S. Cl.

USPC **D30/121**

(57) **CLAIM**

The ornamental design for the feed stand, as shown and described.

DESCRIPTION

FIG. 1 is a perspective view of the feed stand.

FIG. 2 is a front view of the feed stand, the rear view being a mirror image thereof;

FIG. 3 is a left side view of the feed stand; a right side view is a mirror image of the left side view.

FIG. 4 is a top view of the feed stand; and,

FIG. 5 is a bottom view of the feed stand.

The broken lines showing fastener holes, adapter brackets and an eyelet and associated fastener are for illustrative purposes only and form no part of the claimed design.

1 Claim, 5 Drawing Sheets
